(57) **CLAIM**

The ornamental design for a middle cab of an overhead suspended train, as shown and described.

DESCRIPTION

FIG. 1 is a perspective view of a middle cab for an overhead suspended train showing my design;

FIG. 2 is a top plan view of the middle cab of FIG. 1;
FIG. 3 is a bottom plan view of the middle cab of FIG. 1;
FIG. 4 is a side elevational view of the middle cab of FIG. 1, it being understood that the left and right sides of the middle cab are mirror images of one another; and,
FIG. 5 is a front elevational view of the middle cab of FIG. 1, it being understood that the front and rear walls of the middle cab are mirror images of one another.

In the views of FIGS. 1 and 5, broken lines are used to illustrate the possible placement of doors in the middle cab. The structure shown in broken lines forms no part of the claimed design.
